[57] CLAIM

The ornamental design for an optical disk/cartridge library without internal controller, as shown and described.

DESCRIPTION

FIG. 1 is a front view of an optical disk/cartridge library, or the like, showing our new design;

FIG. 2 is a top view thereof;

FIG. 3 is a bottom view thereof;

FIG. 4 is a left side view thereof;

FIG. 5 is a right side view thereof;

FIG. 6 is a rear view thereof; and,

FIG. 7 is a perspective view from the top, front, and right sides thereof.

*FIG. 1**FIG. 2**FIG. 3*

FIG. 4

FIG. 5

FIG. 6

FIG. 7
